CLAIM

The ornamental design for a handle grip for a luggage or a hard case bag, as shown and described.

DESCRIPTION

FIG. 1 is a front perspective view of a luggage or hard case bag, having a handle grip wherein the handle grip is on bottom of the luggage or the hard case bag, showing my new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof;

FIG. 7 is a bottom plan view thereof;

FIG. 8 is an exploded view thereof;

FIG. 9 is an enlarged perspective view of the handle grip separately;

FIG. 10 is a front elevation view thereof;

FIG. 11 is a rear elevation view thereof;

FIG. 12 is a left side view thereof;

FIG. 13 is a right side view thereof;

FIG. 14 is a top plan view thereof; and,

FIG. 15 is a bottom plan view thereof.

The broken lines showing luggage are for the purposes of illustrating environment and form no part of the claimed design.
